ART OF HANDLING, CONVEYING, AND
TREATING BULK FIBROUS AND OTHER
MATERIALS

Nelson B. Henry, Columbus, Ga.

Application January 4, 1933, Serial No. 650,195

11 Claims. (Cl. 19—74)

My invention relates generally to improvements in the art of handling, conveying and mechanically treating bulk, fibrous, and other materials,—the invention having especial reference to the cleaning, mixing and distributing of fibrous material such as cotton,—and being an improvement over the disclosures of my co-pending application, Serial Number 520,430, filed March 5, 1931.

Inasmuch as a very important phase of the present invention has to do with the matter of cleaning cotton or the like,—brief reference to the various customary cleaning procedures is desirable in order to obtain a full understanding of the advantages of my advance in the art, as disclosed herein.

Cotton has heretofore been cleaned in three ways:

- (1) By beating over feed rolls and grid bars.
- (2) By rotating in a vertical or horizontal screen or grid cylinder, with or without a current of air.
- (3) By passing it over grid bars or a screen by means of a rapidly moving current of air.

All of these three ways have serious disadvantages, and have only been used for want of a better method.

Beating cotton over feed rolls and the grid bars before it is thoroughly opened, breaks up the leaf, motes and neps, as well as some good fibers. It may actually increase the percentage of fine trash in the stuff, and this is the most difficult class of foreign matter to remove.

Adverting to the second cleaning method,—(2) supra,—rotating or whirling cotton at high velocity has a decided tendency to curl and twist the fibers. Where the stock is rotated against grid bars, the retarding action of these grids greatly aggravates this trouble.

Thirdly, the passing of the cotton over grids or screens by a rapidly moving air current has very little cleaning effect, as the fine trash floats with the air and passes through the trunk with the cotton. Furthermore, nothing can be put in such a trunk to open the stock and liberate the heavier trash so that it can fall through the grids.

The present invention, therefore, has for one of its primary objects to overcome the foregoing objections by the provision of a new method and apparatus for the opening, cleaning and handling of cotton and the like,—the nature of the invention being such that the cotton fibers will not be twisted, curled, or broken; and also assuring against the breaking up of leaf, motes, neps, and

the like to increase the percentage of fine foreign matter in the cotton and cause trouble in subsequent picking, carding, and other processes.

Another important object of the invention is to provide a novel apparatus for cleaning and otherwise treating cotton which will require much less power to operate than is required by prior devices,—the nature of the apparatus being such that it will be easily installed, and inasmuch as it has a minimum number of simple and durable parts, it may be operated over long periods of time without inspection or repair.

Another phase of the invention has to do with the mixing of cotton and the distributing of it to various bins or machines,—in which respect the present invention is an improvement over the invention disclosed in my co-pending distributor application,—the present invention contemplating novel means whereby different lots of cotton, such as bales, may be mixed together in a predetermined ratio so as to pass on for subjection to picking and carding processes a mass of cotton which is uniform in quality, and which will represent the average of the various bales that are opened up and supplied to the apparatus.

The invention furthermore contemplates the provision of means for controlling the supply and mixing of the cotton,—which means preferably comprehends automatic operation, and there being means for effecting such automatic operation, which means is preferably operated by the cotton.

The invention furthermore contemplates a device for the purpose specified which may be provided in sections arranged in various ways so as to economize floor space and produce the requisite amount of cleaning and mechanical treatment of the cotton or other fiber.

Another object of the invention is to provide for the cleaning and mechanical treatment of the cotton or other fibrous materials which comprehends the subjection of the mass of cotton to a gyratory action of flexible whipping instrumentalities entering the mass of cotton from above and pressing forwardly and downwardly and then rising up out of the cotton while still moving forwardly, whereby to loosen the fibers and permit dirt to settle to the bottom of the trough or the like, which bottom will have a grating or screen for the escape of dirt.

The invention also resides in certain novel features of construction, combination and arrangement of the various parts, and in certain modes of operation and treatment of the product, as will be readily understood and appreciated by those skilled in the art upon reference to the

following descriptive matter in connection with the accompanying drawings which illustrate one example of the invention.

It will be understood that the disclosures herein are directed to what now appears to be a preferred expression of the invention. Obviously, however, the invention is susceptible of many expressions within the spirit and scope of the subject matter claimed hereinafter.

10 In the drawings, wherein the same reference characters have been used to designate the same parts in all views,

15 Figure 1 is a side elevational view, partly broken, and partly in section and illustrating an installation for mixing, cleaning and distributing cotton to a battery of pickers or other machines which, along with the condenser, are shown merely diagrammatically in the drawings;

20 Figure 2 is an end elevational view of the installation of Figure 1;

25 Figure 3 is an enlarged longitudinal sectional view through a portion of the left hand end of the upper section of the device illustrated in Figure 1, and showing the automatic control means for regulating the supply of cotton to the apparatus from the condenser;

30 Figure 4 is a detailed view in perspective of a novel cotton-actuated valve element incorporated in the cotton supply regulating device;

35 Figure 5 is a side elevational view, partly broken and partly in sections illustrating a combination of assemblies, such as is shown in Figure 1, and slightly modified;

40 Figure 6 is an elevational view taken on the plane 6—6 of Figure 5 and looking in the direction of the arrows, and

45 Figure 7 is a detailed top plan view of the discharge means of the horizontal unit.

50 Referring specifically to the drawings, numeral 2 indicates the pickers or other machines for receiving the cotton from the device, and it is to be understood that any number of such pickers or bins may be employed. The pickers or bins 2 are illustrated merely diagrammatically,—as is also the pneumatic condenser 3 of Figure 1, which supplies the cotton to the trough 4 which is upwardly inclined to a point adjacent the condenser, as shown in Figure 1.

55 The incoming cotton from the distributor 3 therefore gravitates down the trough 4 which, as shown, is open at the top, and passes into the upwardly inclined and elongated casing 5. In the illustrated installation, the casing 5 serves as a preliminary cleaner for the incoming cotton preparatory to its passage to the casing section 15, which in addition to subjecting the cotton to further cleaning, distributes it to the various bins or machines 2.

60 In carrying out the invention, the elongated casing 5 is provided with a bottom formed by transverse grate bars 6 forming passages through which dirt may pass into the dirt chamber 7, which is provided with a door or closure 8 for removal of the accumulated dirt. Preferably, there are provided a plurality of dirt chambers 7, extending in series in the direction of the length of the casing 5 as illustrated in Figure 1. The closures 8 for the dirt chambers 7 may be swing closures or any preferred form of closure may be employed including a drawer-like closure.

65 The means for loosening the fibers of the cotton, so as to permit settling of the dirt to the bottom of the casing 5 and into the dirt compartment 7, comprises the crank operated connecting rod structure of my co-pending applica-

tion, and likewise the series of flexible finger members on the connecting rods, which fingers are the elements which engage the cotton, to loosen and actuate it, as aforesaid.

70 As will be noted, the crank shafts 9 of the 5 casing 5 are journalled in bearings 9a and are provided with three cranks each, arranged approximately a hundred and twenty degrees apart, as illustrated. Connecting rods 10 are journalled on corresponding cranks of the respective crank 10 shafts and have the downwardly projecting flexible steel fingers 11. The fingers 11 are preferably disposed in off-set lineal series on each of the connecting rods 10,—that is to say, the outer ends of adjacent fingers extend laterally in opposite directions, so as to avoid grooving of the cotton and also to provide for a better loosening action upon the cotton when the machine is in operation.

75 The peculiar advancing action of the fingers 11 and 23 has been described at length in my co-pending application Serial No. 520,430, filed March 5, 1931. A brief reference to the operation will be suggested herein. Having reference particularly to the lower left hand end of 25 casing 5 in Figure 1, it will be noted that as the cranks 9b revolve the respective sets of fingers 11 carried by the links 10 will alternately engage the mass of cotton from opposite sides and in serial relation. At least two sets of the fingers 30 will be continuously engaged with the mass of cotton to insure a steady and continuous advancing movement over the foraminated surface 6. Due to the fact that the various sets of fingers move in operating cycles with a circular motion 35 in planes that are at all times perpendicular to the foraminated surface. It will be apparent that the axis of each finger is at all times perpendicularly disposed with respect to the surface 6 so that the fingers penetrate the material 40 by a direct perpendicular movement and without any angular disposition.

80 As these fingers alternately engage the material at points spaced apart over the area of the mass and laterally with respect to the direction 45 of movement of the mass, there will be a lateral pulling apart of the fibrous material throughout the entire extent of its travel over the foraminated surface 6. This pulling apart loosens and separates the fibers and allows the dirt and foreign material to drop down onto the surface 6 to be passed therethrough in the cleaning of the cotton. An important feature of this operation resides in the fact that the separating pulling on the fibers is always directed in a zone bounded 55 by planes that parallel the surface 6 so that a horizontal pulling action results. In the first stage of treatment throughout the casing 5 the material is separated and cleaned by pulling apart the fibers as the material is advanced up 60 the incline. Upon being transferred through transfer chute 14 to the distributor and cleaning casing 15 the material travels in a plane that is disposed at an angle with respect to its plane of travel within the casing 5. In consequence, the 65 separating action of the fingers 23 within casing 15 pulls the fibers apart from a different angle than the separating pull imparted during travel through the casing 5. This results in a further effective separation of the fibers to a low 70 contained dirt and foreign material to drop through onto the foraminated surface 17.

85 Particular attention is directed to the fact that the casing 5 is disposed at an upward angle with its left hand, or inlet end, supported upon the 75

floor 2a, as illustrated in Figure 1, while its upper outlet end is disposed well above the floor and the tops of the bins or pickers 2. The continually driven crank shafts 9 produce the shaking or loosening of the cotton at different lateral points, so as to separate the fibers, while at the same time propelling the cotton towards the discharge chute 13 at the upper end of the casing 5,—which chute discharges into the inlet chute 14 of the casing 15, to which brief reference has heretofore been made.

The casing 15 is an elongated affair like the casing 5, and has top and side walls; also, a series of grated bottom portions 17 above dirt chambers 15a, which may be provided with suitable doors 16. However, here the dirt chambers and gratings are separated and preferably there is provided between each dirt chamber 15a, a discharge outlet 18, which is flanged as at 18a to carry a preferably flexible discharge chute 19 which empties into the subjacent bin 2.

The upper or horizontal casing 15 has the laterally spaced crank shafts 20 providing the cranks 20a which carry the connecting rods 22, having the flexible steel fingers 23, as shown. The cranks 20 are carried in suitable bearings 21 and they will be driven by means of a pulley 24, keyed or otherwise secured to one of the crank shafts. A similar drive pulley 12 is shown for supplying power from any suitable source for driving the crank shafts 9 of the casing 5.

The left hand or discharge end (Figure 1) of the casing 15 terminates in a downwardly extending chute 25, whose outlet end is arranged above the supply chute 4, so that excess material from the casing 5 that was not discharged through the outlet 18, 19 into the bins 2, may be resupplied through the casing 5 for the purpose of mixing or blending the cotton of a plurality 40 of bales, so as to furnish a uniform mixture or grade of cotton to the bins or pickers 2.

By way of explanation, the quality of cotton in different bales will vary somewhat, and since it is very desirable to supply a uniform grade 45 of cotton to the pickers or carding apparatus, the proper blending and mixing of the contents of different bales presents a serious problem to mill operators.

As heretofore indicated, my invention aims 50 particularly to provide for the proper blending and mixing of cotton so as to provide a uniform quality for supply to the pickers or the like. In carrying out this phase of the invention, I provide the valve 26 which is fixedly carried by the 55 shaft 27 (Figures 1 and 4),—which shaft 27 is journaled in suitable bearings 28 which are adapted for vertical adjustment in slots 29 in each side of the casing 15. Suitable clamp means, such as 28a (Figure 3) may be availed of 60 for supporting the bearings 28 in a predetermined adjusted position for the purpose of maintaining the lower end of the valve 26 a predetermined distance above the plane of the bottom of the casing 15.

In practice, the supply of cotton to the casing 15 is greater than the amount that will drop down the outlets 18, 19 into the bins 2, and consequently there will be an excess of cotton that will be discharged from the left hand end of the casing 15 through the chute 25 and into the supply chute 4, which carries the incoming cotton to the cleaner casing 5. Thus, the contents of different bales are mixed, and the valve 26 is adapted to control this mixing of cotton by regulating the supply of cotton to the trough or chute

4 from the condenser 3. This will all be explained presently, in greater detail.

Figures 1, 3 and 4 illustrate the shaft 27 as having one end provided with a crank arm 30 having an eye 31 at its free end for pivotal engagement with an adjustable link element 32, which may include a screw collar extension 32a or other means for varying its length. The end of the collar 32a is provided with slotted arms receiving the crank pin 33 of a crank lever 34a 10 which forms a part of a switch 34. The switch 34 may be of any desired construction and swinging of the lever 34a tends to make or break an electric circuit 35, which controls suitable means (not shown) for controlling the supply of cotton 15 to the condenser 3.

There are various ways of controlling a supply of cotton to a condenser, and electrically operated means for this purpose are well-known and form no part of the present invention.

It will be understood that when the valve 26 is in the position shown in Figures 1 and 3, the circuit 35 controlled by the switch 34 will be opened and a constant supply of cotton to the trough or chute 4 will be had.

The operation of the device may be summarized as follows:

The cotton is supplied to the trough or chute 4 from the condenser 3 and gravitates down said chute to the lower end of the upwardly inclined 30 cleaner unit or casing 5. The operation of the cranks 9 cause the flexible fingers 11 to engage the cotton and to progressively advance same toward the upper end of said casing 5. As the fingers 11 are driven in a circular path and enter 35 into the cotton from above, following a circular path in the direction of the upper end of chute 5, it will be plain that there will be an effective loosening of the fibers, or an opening action, which will permit the dirt and foreign matter to 40 settle to the bottom of the casing 5 and fall through the screen or grating 6 into the dirt compartments 7.

Particular stress is laid upon the fact that cranks and connecting rods are disposed laterally 45 of one another and come successively into action. This results in a very effective loosening of the fiber, in that the forward or advancing action of the cotton up the casing 5 is accompanied by successive lateral impulses due to 50 the lateral spacing of the connecting rods and the series of fingers carried thereby. The spring metal fingers 11 operate with a kind of whipping action which is very effective in loosening and separating the cotton, but will not damage the 55 fibers; nor will it break or pulverize motes, neps, leaf or the like, to increase the percentage of finely divided foreign matter which is so difficult to remove. The action of fingers 11 throws the cotton violently against the grids or screen 60 bars 6 at each stroke of the respective connection rods. While an effective cleaning, opening and loosening action is produced, yet the action of the fingers 11 cannot cause the least curling, twisting or stringing of the fibers, regardless 65 of the length of the casing 5.

Since it takes an appreciable period of time for the cotton to pass through the casing 5 while being thoroughly agitated, there is ample opportunity for the separated trash to drop through 70 the grid bars. It should be borne in mind that there are no air currents to hold the light trash in suspension and carry it along with the cotton.

By the time the cotton reaches the upper end of the inclined casing 5, it is pretty thoroughly 75

cleaned and is discharged through the outlet chute 13 into the inlet chute 14 of the casing 15,—which chute 14 discharges the cotton into casing 15 below the connecting rods 22, to be acted upon by the spring fingers 23 which correspond to the spring fingers 11 of chute 5.

The cleaning action is continued in the casing 15 and as the cotton passes over the several outlets 18, 19 above the pickers or bins 2, a certain amount of cotton will drop down into such bins.

As in my co-pending application, this distributor phase of the present invention provides the supply of a uniform quantity of cotton to the bins 2. It is to be particularly noted that the overflow of cotton passing from the casing 15 to the chute 25 combines with the incoming cotton from succeeding bales and passes again through the machine for further cleaning and mixing. It is thus to be seen that within reasonable limits the overflow cotton may bear any ratio to that cotton deposited in the bins or pickers 2.

While the incoming supply of cotton through condenser 3 can never exceed the total cotton fed to the hoppers or bins 2 over a period of time, yet it can be so controlled as to provide a very large overflow in proportion to the cotton passing to the bins or pickers 2 in a particular passage or cycle. By way of illustration, a particular mass or quantity of cotton is passed over the openings or outlets 18, 19. Some of this particular mass of cotton will drop down into the bins and some of it will be carried on and discharged from the left hand end of the casing 15 through the chute 25.

It is, of course, to be understood that cotton is being continuously removed from the pickers 2 by means of a feeder apron (not shown) and passed on to the picking machinery. This is well known, and does not form a part of my invention.

By increasing the amount of overflow cotton, the mixing and cleaning will be proportionately increased. For example, assume that the overflow cotton from the chute 25 exactly equals the amount of cotton that is passing into the bins or pickers 2. From this it will be readily appreciated that the overflow cotton will at that particular time, be one-half the amount fed down the chute 4 from the condenser. Assuming that, of this augmented supply, the same amount of cotton is fed into the bins or pickers 2, it is then apparent the overflow through chute 25 will equal the feed from the condenser, and if the same conditions continued on the next round the overflow would considerably exceed the feed from the condenser. However, this condition soon brings about a shifting of the valve 26 and cuts down the feed from the condenser so that the starting proportions are resumed, with the result that through these varying cycles, the overflow may be regulated to an average by which it will approximately equal the incoming cotton and that the two will be mixed on an approximately fifty-fifty basis. By increasing the overflow cotton to two or three times the quantity passing through the hoppers, it is readily seen that the mixing and cleaning effect is correspondingly greater.

The height of the valve 26 is initially set so as to allow a predetermined quantity of cotton to pass below the lower end of the valve 26, without engaging and swinging the same forwardly to operate the switch 24 and cut off the supply of cotton from the condenser 3.

Thus, the valve 25 serves to regulate the supply of cotton from the condenser in proportion to the overflow through chute 25. Thus, choke ups are

prevented, and the ratio of overflow of cotton will be maintained with respect to the supply from the condenser.

Figures 5, 6 and 7 illustrate, in effect, a combination of two assemblies illustrated in Figure 1,—but with slight modifications. While the illustrated arrangement comprehends the discharge from one horizontal member into the inclined member of the other assembly and vice versa; and I have illustrated novel means for bringing this about,—yet it will be obvious that other arrangements of sets of these assemblies can be employed.

The arrangement of Figures 5, 6, and 7 becomes of particular advantage where six or more pickers or bins 2' are to be fed. It should be understood that each picker requires from three to four hundred pounds of cotton an hour. The capacity of one of my assemblies such as is illustrated in Figure 1 is approximately twenty-five hundred pounds of cotton per hour, which means that there would be very little, if any, overflow in case six or more pickers are fed from one cleaner-distributor assembly. As have been already emphasized in connection with Figure 1, efficient cleaning and proper mixing requires a substantial overflow from the horizontal member of the assembly.

Figure 5 illustrates two assemblies,—each of which is substantially identical with what is shown in Figure 1. For purposes of description and in order to differentiate the inclined casing or cleaner section of one assembly is designated as at 5', while the corresponding casing of the other assembly is designated as at 5''. The horizontal casing or distributor section of the first mentioned assembly is designated as at 15', while the corresponding casing of the other assembly is designated as at 15''.

Except as hereinafter noted, the two assemblies are identical, and hence a description of one will suffice for both.

The dirt compartments of the inclined casing section 5' are designated as at 7' and have doors 8', that is except as to the lowermost section which rests upon the floor. This section has a dirt chamber 7'' providing a base and there is a drawer 8'' which catches the dirt and can be removed. Obviously, any other form of closure could be employed in place of the drawer 8''.

The crank members 20', the connecting rods 10', the flexible fingers 11', the grate bars 6', all correspond to similarly numbered but primeless parts in Figure 1. This also applies to the pulley 12' and the communicating troughs or passages 13', 14', whereby the material is discharged from the inclined casing 5', (or 5'') into the horizontal casing or member 15' (or 15'').

The casings 15', 15'' have the dirt compartments 15x with the doors 16' and intermediate the dirt compartments, the outlets 18' carrying the flexible conduits 19' for the discharge of the material into the subjacent pickers or hoppers 2'.

The inclined casings 5', 5'' are partly supported by the base sections providing the dirt chambers 7', and partly by the upstanding posts 41,—it being observed that the casings 5', 5'' and 15', 15'' are made in separable sections adapted to be connected together as indicated at 40.

From what has been said, it will be obvious that the base portions of the dirt compartments 7'' cooperate with the posts 41 in supporting the inclined sections 5', 5''.

I have also illustrated the horizontal casings 15', 15'' as provided at their adjacent discharge 75

ends with the adjustable valves 26 and switching means 34 adapted to be operated thereby as illustrated in Figures 1 and 3.

Resting upon the floor between the two units 5 is the hopper member 43 having the lateral inlet 43a at one side for feeding cotton or other material to both of the inclined casings 5', 5''. In this connection, it will be observed that connecting rods 10' have rake-like extensions 10x 10 which angle upwardly slightly in prolongation of the connecting rods 10' so that the prongs will project towards the bottom of the hopper 43. It will be obvious that the rake-like extensions 10x of the connecting rods 10' of each upwardly inclined unit 5', 5'' will operate to remove the cotton from the hopper 43 for supplying the respective assemblies.

The operation is just the same as described in connection with Figure 1, until the cotton gets 20 to the opposed discharge ends of the horizontal casing sections 15', 15''. Of course, the valves 26 will be adjustable as before so that a predetermined amount of cotton may pass beneath without engaging the valves and causing them to operate the switches 34 for cutting off the supply of 25 cotton from the condenser to the side inlet portion 43a of the hopper 43.

A very important feature of novelty in connection with the structure of Figures 5, 6 and 7 is the 30 chute means in association with the hopper formation 43 whereby the overflow from the casings 15' will be discharged into the portion of the hopper 43 adjacent the inlet to the inclined chute 5'' of the other assembly,—and vice versa.

In carrying out this phase of the invention, the 35 casing 15'' has its outlet end provided with the chute portion 44 having, as best illustrated in Figure 7, the lateral material deflecting wall 44a, which guides the material from the casing member 15'' into the forwardly inclined trough portion 46 which communicates with the passage 46a of the hopper 43 which discharges into said hopper adjacent the upwardly inclined casing 5'. Thus, the overflow from the casing 15'' of one 45 assembly is supplied to the upwardly inclined casing 5' of the other assembly.

The discharge end of the casing 15' has a chute portion 45 (Figure 7) which has the laterally inclined wall 45a, corresponding to the wall 44a of the chute 44, but inclined at the opposite side and emptying into the chute portion 47 which is disposed laterally of the chute portion 46 and discharges into the passage portion 47a of the hopper 43. The passage 47a of the hopper 43 discharges the material received from the horizontal casing 15' adjacent the inlet end of the upwardly inclined chute 5''. Thus, the overflow from casing 15' is supplied to upwardly inclined casing 5'' and there will be provided a very efficient mixing 50 of the cotton and in addition a wide ratio of mixing of cotton can be effected, and at the same time six or more pickers can be supplied without exceeding the capacity of the machine or running it at high speed.

Particular attention is directed to the fact that, 55 as shown in Figure 6, the passages 46, 47 of the hopper 43 empty into such hopper adjacent the bottom thereof and at the opposite side of the hopper from the normal initial feeding opening 43a. Thus, there will be an efficient mixing of the initially fed cotton with that which has been run through the machine and discharged from the overflow. The arrangement of Figure 7 not only mixes the incoming cotton with that which has 60 gone through the machine before, but also passes

the overflow that came from one machine to the inlet casing 5' (or 5'') of the other machine. The mixing is therefore very efficient.

The assembly of Figure 5 supplies a battery of 5 six pickers but by the arrangement illustrated is enabled to do so without exceeding the capacity of the machine, and gives the operator a wide choice as to the proportion of overflow to be mixed with the incoming cotton,—it being remembered that the capacity of each assembly, as 10 shown in Figure 1, is about twenty-five hundred pounds per hour, while the pickers 2 (2') will require from three hundred to four hundred pounds of cotton per hour.

The arrangement of Figure 5 and of the various component parts thereof can of course be modified considerably. The parts crank shafts, 15 cranks, connecting bars and fingers of Figure 5 correspond in all respects to the parts 20, 20a, 22 and 23 of Figure 1.

Having thus described my invention, what I claim is:

1. A cleaning and distributing apparatus for cotton and the like, comprising an elongated inclined feeder and cleaner casing having a dirt 25 compartment in its bottom, screen means separating the dirt compartment from the casing, a horizontal distributor casing into one end of which the upper end of said feeder opens, lineal series of flexible fingers extending toward the 30 screen of said feeder and the base of said distributor, carriers for said fingers and extending in the direction of the lengths of said casings, and means for gyrotrarily driving said carriers for periodically moving said fingers into engagement with the cotton to actuate it toward said screen and in an advancing direction toward the discharge end of each of said casings.

2. The combination set forth in claim 1 where-in the distributor casing has material outlets 40 and gratings between said outlets, and said fingers operate above said outlets and gratings.

3. The combination set forth in claim 2, and including a plurality of flexible finger series in each casing and a carrier for each series, and 45 means for successively actuating said carriers to engage the respective finger series with the cotton at laterally spaced points in said casings.

4. An apparatus for blending, cleaning and distributing cotton and the like comprising a 50 pair of elongated casings arranged substantially end to end and having dirt outlet openings along their bottoms, laterally spaced and lineally extending gyrotrary members in said casings, each of said gyrotrary members having a lineal series 55 of spaced and flexible material engaging elements, a common feed hopper between said casings, said gyrotrary members having rake-like extensions movable into said feed hopper, and conduit means associated with said feed hopper 60 and casings for discharging material from one casing into the other at the site of said hopper.

5. The combination set forth in claim 4, the conduit means at one side of said hopper and a new material inlet at the other side. 65

6. The method of cleaning cotton, which consists in moving a mass of such cotton over a foraminated surface, and at the same time applying a separating pull to the fibers thereof in a direction substantially lateral to that of movement of 70 the mass during the entire extent of movement of the mass.

7. The method of cleaning cotton, which consists in moving a mass of such cotton over a foraminated surface, and at the same time alter- 75

nately pulling apart the fibers thereof in opposite directions laterally of the direction of movement of the mass during the entire extent of movement of the mass.

5. 8. The method of cleaning cotton, which consists in moving a mass of such cotton over a foraminated surface, and at the same time constantly pulling apart the fibers thereof in opposite directions laterally of the direction of movement of the mass during the extent of movement of the mass.

10. 9. The method of cleaning cotton, which consists in moving a mass of such cotton over a foraminated surface, and at the same time simultaneously and constantly pulling apart the fibers thereof in opposite directions laterally of the direction of movement of the mass, from points spaced apart over the area of the mass during the extent of movement of the mass.

15. 10. The process of cleaning locks of cotton which consists in supplying a mass of such cotton to a substantially flat foraminated surface,

engaging the mass by a plurality of penetrating fingers, arranged in sets disposed axially of the direction of movement of the mass and moving the sets of fingers in staggered circular operating cycles through planes perpendicular to the foraminated surface, whereby to propel the mass over said surface.

5. 11. In an apparatus for handling locks of cotton, an inclined delivery chute, means for supplying a constant excess of cotton thereto, means for simultaneously conveying and cleaning cotton delivered from said chute, means for distributing cotton delivered from said combined conveying and cleaning means, means for discharging excess cotton from the distributing 10 means into said chute to mix with fresh cotton supplied thereto, and means operable by material in a portion of said excess cotton discharging means for automatically controlling the proportion of fresh and excess cotton at the delivery 15 end of said chute.

NELSON B. HENRY.
